INVENTOR:

Frederick Medart,

by Robert Burns

Attorney.

UNITED STATES PATENT OFFICE.

FREDERICK MEDART, OF ST. LOUIS, MISSOURI.

HORIZONTAL-BAR EXERCISING APPARATUS.

SPECIFICATION forming part of Letters Patent No. 475,697, dated May 24, 1892.

Application filed August 10, 1891. Serial No. 402,297. (No model.)

To all whom it may concern:

Be it known that I, FREDERICK MEDART, a citizen of the United States, residing at St. Louis, in the State of Missouri, have invented 5 certain new and useful Improvements in Horizontal-Bar Exercising Apparatus; and I do hereby declare the following to be a full, clear, and exact description of the invention, such as will enable others skilled in the art to which 10 it appertains to make and use the same.

This invention relates to improvements in horizontal-bar exercising apparatus for gymnasiums.

The object of the present improvements is 15 to provide an improved construction of such apparatus embodying the features of a firm and substantial attachment of the vertical posts or uprights to the gymnasium-floor in a manner to admit of their ready removal 20 when required, means for effecting an adjustment of the posts or uprights to a true vertical position, and a simple and efficient construction of the socket, whereby it can be readily adapted to the floor of a gymnasium 25 in a manner to admit of the shrinkage of the joists thereof being compensated for. I attain such objects by the construction and arrangement of parts illustrated in the accompanying drawings, in which—

30 Figure 1 is a sectional elevation of a horizontal-bar exercising apparatus constructed in accordance with my present invention; Fig. 2, a horizontal section at line α α ; Fig. 3, a plan view of the bottom of the socket-casting 35 and its connections; Fig. 4, a detail sectional elevation of a modification.

Similar figures of reference indicate like parts in the different views.

Referring to the drawings, 1 represents one 40 of the counterpart posts or uprights of the apparatus made of any suitable material and of any suitable cross-section, preferably of channelled iron, in the form of a ribbed letter **H** in cross-section, as shown in Fig 2, for 45 the double purpose of affording ample strength with extreme lightness and at the same time provide vertical channels to receive the ends to the horizontal bar 2 in its different vertical adjustments in use, such 50 horizontal bar being secured to the required

adjustment by means of a cross-pin 3, passing through one of a series of holes 4 in the flanges of the posts 1 and through or under the ends of the horizontal bar 2. (See Figs. 1 and 2.) The lower end of each post 1 is 55 formed with a tapering end 5, which at its union with the main body of the post preferably forms a supporting shoulder or offset 6, as illustrated in Fig. 1. The web of the post is formed with a vertical series of apertures 60 7 for the double purpose of lightness and to afford means for the engagement of a pry or lever in removing the post from its receiving-socket in the floor of the gymnasium. The floor-socket may consist of a single casting, 65 as indicated in Fig. 4, this form being adapted for a limited use in gymnasiums located on the ground floor where the sockets will be required to be set in the earth in a suitable cement bedding. The more extended use of 70 my invention will, however, be in connection with the floors of gymnasiums, and as so used the floor-socket will consist of an upper and lower member 8 and 9, secured, respectively, in a recess in the flooring and to the bottom 75 of the floor-joists, and substantially connected together by tie-bolts 10, as shown. The upper socket member 8 is formed with a surface recess 11 of a somewhat greater area than that of the post, so as to readily receive 80 the horizontally-adjustable bolts 12 in the post and form an abutment for the same as they are screwed in or out to effect the proper vertical adjustment of the post, as well as the securing of the same solidly in an erect position. The 85 lower socket is provided with rabbets 13, that enter gains cut in the joists, as shown, so as to better retain its proper position, and is provided with a downwardly-extending sleeve 14, through which the series of radial horizontally-arranged adjusting-screws 15 pass to 90 engage and adjust the extreme lower end of the post.

The means of adjustment described is a very valuable feature of construction in that 95 it affords means for adjustment, when from any accidental causes—such as shrinkage of the floor and joists, &c.—an adjustment of the posts or uprights is necessitated. Such means are not, however, absolutely requisite and 100

may be dispensed with and a very useful construction still provided.

Having thus fully described my said invention, what I claim as new, and desire to secure by Letters Patent, is—

1. In a horizontal-bar exercising apparatus for gymnasiums, the combination of a post or upright 1, having horizontal screws 12, and the floor-socket provided with a surface recess 11 10 to receive the same, substantially as set forth.
2. In a horizontal-bar exercising apparatus for gymnasiums, the combination of a post or upright 1 and a floor-socket therefor formed of an upper and lower member bolted together 15 and to the floor by tie-bolts, substantially as set forth.
3. In a horizontal-bar exercising apparatus for gymnasiums, the combination of a post or upright 1 and the floor-socket provided with 20 a series of radial horizontally-arranged screws 15, adapted to engage and adjust the extreme

lower end of the post or upright, substantially as set forth.

4. In a horizontal-bar exercising apparatus for gymnasiums, the combination, with the 25 floor-socket, of a post or upright having a ribbed letter H formation, the flanges of which are formed with a vertical series of holes 4 for effecting an adjustment of the end of the horizontal bar, substantially as set forth. 30

5. In a horizontal-bar exercising apparatus for gymnasiums, the combination, with the floor-socket, of a post or upright having a ribbed letter H formation, the web of which is formed with a vertical series of apertures 35 7, substantially as set forth.

In testimony whereof I affix my signature in presence of two witnesses.

FREDERICK MEDART.
